ABSTRACT: A toy having a body, a boom, and a member supported by the boom and controlled by a cable. A reel and a driven member are mounted upon a shaft journaled in said body. One end of the actuating cable is connected to the reel. A sector member is pivotally connected to said body. Drive means responsive to the pivotal movement of the sector member engages said driven member. An actuator is operable to pivot said sector member whereby the cable may be taken up or let out by said reel to actuate the boom supported member.

TOY SIMULATING A BOOM CARRYING MACHINE

SUMMARY OF THE INVENTION

This invention relates to an improved toy simulating a boom carrying machine, such as a crane or a power shovel, having a body, a boom, and a member supported by the boom and controlled by a cable. A shaft is journaled in said body and has a reel fixedly mounted thereon. The actuator cable has one end connected to the reel so as to be taken up or let out upon the rotation of the reel. A driven member is fixedly mounted upon the shaft which carries the reel. A sector member is pivotally connected to said body. Drive means responsive to the pivotal movement of the sector member engages the driven member. Means manually actuated by the user is provided for causing selected pivotal movement of said sector member whereby the cable may be taken up or let out by said reel to actuate the boom supported member controlled by the cable.

The toy of this invention includes an actuating assembly which consists of a minimum number of component parts which can be easily operated by a small child to actuate a boom supported member. The parts of this unique actuating assembly are of strong and substantial construction, thereby enabling the toy to be roughly handled by a child without breakage.

Accordingly, it is an object of this invention to provide a toy of this type which is of strong construction and which has a long useful life.

It is another object of this invention to provide a toy with a boom and a boom supported member, such as a digger, having simplified means of actuating the boom supported member.

Still a further object of this invention is to provide a toy having an actuating assembly which is of rugged and simple construction.

Other objects of this invention will become apparent upon a reading of the invention's description.

BRIEF DESCRIPTION OF THE DRAWINGS

FIG. 1 is a side elevation of a toy constructed in accordance with the teachings of this invention and having a clam shell bucket attached thereto and supported by a boom.

FIG. 2 is a top plan view of the toy shown in FIG. 1.

FIG. 3 is a fragmentary view of the bucket and boom of the toy as viewed along line 3-3 of FIG. 1.

FIG. 4 is a fragmentary vertical sectional view of the toy with parts shown in section taken along line 4-4 of FIG. 2.

FIG. 5 is a fragmentary cross-sectional view of the toy actuating assembly taken along line 5-5 of FIG. 4.

FIG. 6 is a cross-sectional view of a cable reel taken along line 6-6 of FIG. 2.

FIG. 7 is a fragmentary side elevation of the toy of this invention having a bucket scoop attached thereto.

FIG. 8 is a side elevation of the toy of this invention having a back-hoe attached thereto.

FIG. 9 is a fragmentary top plan view of the toy shown in FIG. 8.

FIG. 10 is a fragmentary detail view of an actuating cable sheave unit which is mounted atop the body of the toy illustrated in FIG. 8 and which shows in broken lines a cover portion in open position.

FIG. 11 is a fragmentary sectional view taken along line 11-11 of FIG. 10.

FIG. 12 is a fragmentary sectional view taken along line 12-12 of FIG. 10.

FIG. 13 is a fragmentary side elevation of a modified construction of the actuating assembly of the toy.

FIG. 14 is a fragmentary side elevation of another modified construction of the toy actuating assembly.

FIG. 15 is a fragmentary side elevation of another modified construction of the toy actuating assembly.

DESCRIPTION OF THE PREFERRED EMBODIMENTS

The preferred embodiments illustrated are not intended to be exhaustive or to limit the invention to the precise forms dis-

closed. They are chosen and described in order to best explain the principles of the invention and their application and practical use to thereby enable others skilled in the art to best utilize the invention.

5 The toy illustrated in FIGS. 1 to 6 includes a frame or carriage 10 having two spaced pairs of wheels 12 mounted thereto. The forward wheels are preferably swiveled so as to facilitate turning of the unit. A body 14 which simulates a cab of a power shovel or crane is carried by frame 10 and is preferably pivoted at 15 about a substantially vertical axis. Body 14 is centered laterally of frame 10 and includes a bottom panel or floor 70, outer substantially parallel side panels 16 and a top panel 18 which may be utilized as a seat by the child operating the toy. An elongated rigid boom 20 extends forwardly and upwardly from body 14. Boom 20 includes forwardly converging spaced parts 22 each of which has one end secured to a transverse shaft 24 extending through side panels 16 of body 14. The other ends of boom parts 22 are secured to a connector or sheave cover 26. A shaft 28 extends transversely through sheave cover 26 and the forward ends of boom parts 22. One or more sheaves 30 are journaled upon shaft 28 within sheave cover 26, and where multiple sheaves are used they are spaced apart by a washer or spacer 32. Boom 20 is positioned relative to body 14 by a pair of braces 34 each of which has one end secured to a side panel 16 of body 14 and the other end secured to a boom part 22 intermediate its length.

20 A body lock member 21 is pivotally connected to the bed 23 of frame 10 and is positioned centrally thereof and just forwardly of body 14. Lock member 21 is pivotal in a direction fore and aft of the frame and has its free end swingable between boom parts 22, as shown in FIG. 1, to lock the body 14 in position extending lengthwise relative to the frame. A handle 35 may be secured to the parts 22 at the forward end of boom 20 to enable the toy to be pulled manually when the body is locked.

25 A pair of spaced inverted channel-shaped housings 60 are disposed longitudinally in laterally spaced relation within the body 14. Each housing 60 includes spaced parallel side walls 62 and 63 which are interconnected at their tops by web 64 and which have lower outturned flanges 66. Each housing 60 may be secured within body 14 by securing means, such as screws 68, extending through apertures in its flanges 66 and anchored in floor 70 of the body.

30 A sector member 72 is pivotally mounted within each housing 60, as by means of a pin 74, extending between walls 62 and 63, as shown in FIG. 5, so as to be swingable in a fore and aft direction within the housing. Two spaced idlers 76 and 77 are journaled in each housing 60 above and in substantially the same plane as sector member 72.

35 The side wall 63 of each housing 60 mounts one or more bearings 53 which journal a shaft 52 extending through an aperture therein. Each shaft 52 is positioned forwardly of idlers 76 and 77 and is spaced from arcuate edge 73 of sector member 72. A driven member 78, such as a pulley, is mounted on the shaft 52 within housing 60 and preferably lies in substantially the same plane as idlers 76 and 77 and sector member 72. An endless flexible drive member 80, shown in FIG. 4 as a flat belt, is trained about idlers 76 and 77 and driven member 78. Driven member 78, idlers 76 and 77 and sector member 72 within each housing 60 are so positioned relative to each other that at least a portion of arcuate edge 73 of sector member 72 engages a run of drive member 80 in a drive transmitting relationship. In order to assure positive drive transmission between sector member 72 and the engaged run 81 of drive member 80 during pivotal fore and aft movement of the sector member, the drive member 80 may be secured to sector member 72 between member 78 and idler 76 by a securing means 82, such as a screw or a staple.

40 FIG. 13 illustrates the use of a corrugated or toothed flexible belt as drive member 80. Arcuate edge 73 of sector member 72, idlers 76 and 77 and driven member 78 are also formed with teeth which mesh with the teeth of the belt. FIG.

45 75

14 illustrates the use of a metal link chain as drive member 80. Arcuate edge 73 of sector member 72, idlers 76 and 77 and driven member 78 of this embodiment are gears whose teeth mesh with the chain. FIG. 15 illustrates another embodiment of the toy actuating assembly in which arcuate edge 112 of a sector member 110 is toothed and meshes with a toothed rotatable driven member 114. Driven member 114 is secured to shaft 52 journaled in housing 60.

A reel 42 is secured to the end of shaft 52 which extends outwardly from housing 60. A pair of spaced elongated handles or levers 84 extend upwardly from and are pivoted to shaft 24 at the front of body 14 between boom braces 34. Each handle 84 is positioned substantially in the plane of a channel housing 60. One or a pair of laterally spaced parallel connecting links 86 are connected at one end at 88 to each handle 84 and extend rearwardly therefrom into the forward open end of body 14 and alongside channel housing 60. Each link 86 is pivotally connected at its opposite end to a sector member 72.

Each sector member 72 has an aperture 92. A rod 90 is preferably press fit into each aperture 92 and has its end portions extending through registering arcuate slots 93 in side walls 62 and 63 of the supporting channel housing 60 and through apertures in the ends of the straddling connecting links 86 which are positioned outwardly and adjacent the housing side walls. Each end of rod 90 preferably has a transverse bore which is located outwardly of the engaging connecting link. Cotter pins 94 are inserted through the bores in the ends of each rod 90 to retain the connecting links upon the rod. The length of each handle 84 is such that a handle grip 85 carried by the handle at its upper end is within easy reach of a child sitting on the top panel 18 and straddling panels 16 of body 14.

A rope or cable 36 is trained over each boom sheave 30. One portion of each cable 36 extends downwardly and rearwardly from its supporting sheave into body 14 where it is attached to a reel 42 by any suitable means, such as a closed loop 44 at the cable end fitting around a pin 46 which protrudes into a bore 48 in the core 50 of the reel as shown in FIG. 6. The other part of each cable 36, which extends downwardly from the sheave 30, is connected to a boom supported member. The boom supported member is illustrated in FIG. 1 as a clam shell bucket 38 having pivoted scoop halves 39. The construction of the bucket 38, the manner of attachment of cables 36 to the bucket parts, and the manner of operation of the bucket upon relative movement of attached cables 36 are well known in the art and are fully explained in U.S. Pat. No. 2,698,691.

To actuate cables 36, the child sits upon body 14 and grasps each handle at a grip 85. Each handle 84 may be swung about shaft 24 in a fore and aft direction with respect to body 14. Movement of one handle controls the vertical positioning of the bucket 38 and movement of the other handle controls the opening and closing of the bucket scoop halves 39. The fore and aft movement of each handle 84 causes a fore and aft rocking movement of the sector member 72 to which it is connected by link 86. This rocking movement of a sector member 72 causes movement of the flexible drive member 80 to which it is anchored at 82, and in turn causes rotation of a reel 42. As a reel 42 is rotated, a cable 36 wound thereon is taken up or payed out, depending upon the direction of rotation of the reel, to thereby actuate the clam shell bucket 38. An arcuate cover 43 extends laterally between channel housings 60 to the rear of reels 42. Cover 43 parallels a portion of the circumferential periphery of reels 42 and is preferably spaced a distance less than the diameter of a cable 36 from each reel 42 so as to prevent the cables from jumping the reels during actuation of the toy.

Modified constructions of the toy are shown in FIGS. 7 and 8. In both constructions, boom 20 is pivoted about shaft 24 and carries either a scoop 94, as shown in the FIG. 7 construction, or a back-hoe 96, as shown in the FIG. 8 construction. In FIGS. 7, 8, 9 and 10, a bracket 98 is attached to body 14. Bracket 98 may include two spaced parallel walls 99 which extend upwardly between reels 42 and which journal a transverse shaft 100. Shaft 100 has end portions which extend outwardly from the outermost sides of walls 99 and which carry a sheave 30 at each end thereof. Cables 36 extend upwardly from reels 42 and over sheaves 30 and are attached to the boom or digger parts of the toy. A sheave cover 101 is pivoted at 102 between walls 99 and includes offsets or projections 103 at opposite sides thereof at one end which snap into detents or recesses 104 in walls 99 of the bracket 98 when the cover is closed over sheaves 30. In both constructions shown in FIGS. 7 and 8, actuation of cables 36 is accomplished in the same manner as was previously described for the construction shown in FIG. 1.

20 I claim:

1. In a toy having a body, a boom, and a member supported by said boom and actuated by a cable, the improvement comprising a shaft journaled in said body, a reel mounted upon said shaft, said cable having one end connected to said reel, a driven rotatable member mounted upon said shaft, a sector member pivotally connected to said body, and drive transmission means responsive to the pivotal movement of said sector member engaging said sector member and said driven member, said drive transmission means including an idler member journaled in said body spaced from said driven member and an endless flexible drive member trained about said driven member and said idler member, the arcuate edge portion of said sector member having drive transmitting engagement with one run of said flexible drive member, and means for pivoting said sector member.

2. In a toy having a body, a boom, and a member supported by said boom and actuated by a cable, the improvement comprising a shaft journaled in said body, a reel mounted upon said shaft, said cable having one end connected to said reel, a driven rotatable member mounted upon said shaft, a sector member pivotally connected to said body, and drive transmission means responsive to the pivotal movement of said sector member engaging said sector member and said driven member, said drive transmission means including a pair of idler members journaled in said body and an endless flexible drive member trained about said driven member and said idler members, the arcuate edge portion of said sector member having drive transmission engagement with a run of said flexible drive member between said drive member and one of said idler members, and means for pivoting said sector member.

3. A toy having a body, a boom, and a member supported by said boom, first and second cables, said first cable actuating said member, said second cable actuating one of said member and said boom, first and second shafts journaled in said body, first and second reels mounted upon said first and second shafts respectively, said first and second cables connected to said first and second reels respectively, first and second driven members mounted upon said first and second shafts respectively, first and second sector members each pivotally connected to said body, first and second drive transmission means responsive to the pivotal movement of said first and second sector members and each engaging a said sector member and driven member, and first and second means for pivoting said first and second sector members respectively, whereby each said cable may be taken up and let out independently of the other cable.
